Des. 37

Addison Low (by Assignees Ralhbae &c.) Albany N.Y.
Letters Patent (Design No. 37.) Dated 7th October 1845.

The schedule referred to in these Letters Patent and making part of the same.

To all whom it may concern: Be it known that Addison Low of Albany in the County of Albany and State of New York, have invented or produced a new ornamental design for a stone, and I do hereby declare that the following is a full and exact description reference being had to the accompanying drawings making part of this specification in which Fig. 1st represents a stone after my design Fig. 2 the ornaments upon the sides and Fig. 3 those upon the front. The principal ornaments upon the sides are upon the oven door 222 2 which consists of a panel surrounded by a double border of leaves, buds &c inclosing a composition of fruits flowers &c as grapes melons, pears, nuts &c as shewn in the drawings. This panel also appears upon the back of the Stone. The composition upon the fire doors in front (Fig. 3) are nearly similar. Over these doors are represented bundles of reeds inclosed between leaves and tied with crop fillets. A tall vase standing upon a bracket and having a star shaped flower at its top and pendant of leaves hanging therefrom, is placed upon each side. The panels upon the extreme sides are filled with leaves &c.

The figures upon the door & (Fig. 2) are the same as those of the front fire doors; and the portion of Fig. 3 which is merely outlined is symmetrical with the shaded portion. The whole though not easily described in words will easily be understood from the drawings.

What I claim as my invention and desire to secure by letters patent is, the combination of figures or ornaments shown in Figs 2 & 3 and especially the composition upon the oven and fire doors.
